UNITED STATES PATENT OFFICE.

C. F. ALLEN, OF PAW PAW, MICHIGAN.

IMPROVED CAR-TRUCK.

Specification forming part of Letters Patent No. 77,858, dated May 12, 1868; antedated May 9, 1868.

To all whom it may concern:

Be it known that I, C. F. ALLEN, of Paw Paw, in the county of Van Buren and State of Michigan, have invented a new and useful Improvement in Car-Trucks arranged for six wheels; and I do hereby declare that the following is a full, clear, and exact description of the same, reference being had to the annexed drawings, making part of this specification, in which—

Figure 1 is a perspective view. Fig. 2 is a central, vertical, and longitudinal section. Fig. 3 is a side elevation, and Fig. 4 is a plan.

The same letters are employed in all the figures in the indication of parts which are identical.

My improvements relate to the construction of a six-wheel truck for railroad-coaches. I embody in their construction some of the features of my improvements in trucks, as set forth in the specifications accompanying Letters Patent granted to me on the 24th day of April, A. D. 1866, and on the 18th day of June A. D. 1867, to which I make reference for the more full explanation of such parts as may be shown in the drawings hereto annexed, and also in the patents cited, and not herein fully explained.

My improvements consist in constructing six-wheeled trucks, with a rigid frame maintaining the wheels in the same line at all times, but at the same time enabling them to run over curves in the track by attaching flanges only to the rims of the outer wheels, the middle ones being flat on the periphery; also, in the mode of supporting the car over the middle axle, so that the weight shall be equally distributed upon the three axles, and in balancing the car over the center of the middle axle, giving it, at the same time, lateral support, when needed, outside of the middle wheels.

The following description will enable persons skilled in the art to construct my improved six-wheeled truck.

In the annexed drawings, six wheels are shown united in one truck. The outer ones A are formed with flanges on the inner edges to keep them on the track. The two middle wheels A' may be constructed without flanges. These wheels are rigidly attached in

the usual manner to the axles B, supported in journal-boxes of the ordinary construction, the whole being united in a frame, C, constructed and braced, as fully set forth in the specification accompanying my patent of June 18, A. D. 1867, and as shown in the drawings. The journal-boxes are pressed down by a series of springs, D, placed above the frame, and which are united by the levers D', being connected by stirrups, in the manner clearly shown in Fig. 3. As the boxes have free play between their pedestals the wheels may accommodate themselves within the limits allowed by the tension of the springs to inequalities in the surface of the track. These trucks being placed under each end of the car the latter is attached to them by a king-bolt passing through the plate E, which is bolted to the top of a beam, F, supported by braces G G, connecting it with the swinging beams H, which are placed on each side of, and equidistant from, the middle axle, and extend through and project beyond the frame C. The lateral motion of the car is controlled within limits fixed by the shoulders at H', which are made to bear against the frame, being protected by india-rubber or other springs to mitigate the shock which would otherwise be occasioned by the swinging of the car from side to side. The swinging beams H are placed between the transverse beams I I, the latter being rigidly attached to the frame resting upon the braces supported by wrists resting upon the lower bars of the frame. The swinging beams H rest upon india-rubber or other suitable springs K, supported by the beams L, which are hung upon stirrups M, suspended from the transverse beams I. The sides of the car are supported upon blocks N, sustained on each end of the swinging beams H by braces O extending thereto. The side frames are connected rigidly by means of the beams O', at each end; also, by the transverse beams I.

What I claim as my invention, and desire to secure by Letters Patent, is—

1. So supporting the end of a car upon a six-wheeled truck that the weight shall be equally distributed upon all the wheels by resting it upon a support over, but not upon, the middle axle, said support being sustained

by springs placed on each side of, and equidistant from, the middle axle, and the whole weight being transferred to the axles through a rigid frame, substantially in the manner set forth.

2. In combination with the beam F, the braces G, and swinging beams H, placed on each side of the middle axle, and supporting upon their outer ends the side bearing-blocks N, so as to balance the weight of the end of

the car over the middle axle, substantially in the manner set forth.

In testimony whereof I have signed my name to this specification in the presence of two subscribing witnesses.

C. F. ALLEN.
